SHOE POLISHER AND CONTAINER

John G. Hummel, Warren Point, N. J.

Application November 12, 1934, Serial No. 752,741

1. Claim. (Cl. 15—258)

This invention relates to kits for polishing shoes and has for its primary object the provision of a compact device which will house polish for cleaning and polishing accessories and prevent the loss or misplacement thereof and will prevent soiling of other articles which may come in contact with the device and will be readily accessible for use when desiring to clean or polish shoes.

10 With these and other objects in view, this invention consists in certain novel features of construction, combination and arrangement of parts to be hereinafter more fully described and claimed.

15 For a complete understanding of my invention, reference is to be had to the following description and accompanying drawings, in which

Figure 1 is a side elevation illustrating a shoe polishing kit constructed in accordance with my invention.

20 Figure 2 is a horizontal sectional view illustrating the same.

Figure 3 is an end view, partly in section, illustrating the device.

25 Figure 4 is a sectional view taken on the line 4—4 of Figure 2.

Figure 5 is a sectional view taken on the line 5—5 of Figure 2.

30 Figure 6 is a side elevation illustrating a brush removed from the kit.

Figure 7 is a side elevation illustrating a polish applying brush removed from the kit.

35 Figure 8 is a detail sectional view taken on the line 8—8 of Figure 3.

Referring in detail to the drawings, the numeral 1 indicates a casing of a shape which will provide compactness and has one side fully open to form an entrance 2. End plates 3 are mounted in the casing against the end walls of

40 the latter and extend through the entrance with beveled portions 4 notched, as shown at 5. The plates 3 support a shaft 6 against rotation and on which is journaled a flanged drum 8. A coil spring 9 is mounted on the shaft and has one 45 end fixed to said shaft and the opposite end fixed to the drum for the purpose of rotating the drum in one direction. A polishing cloth 10 is wound on the drum with one end fixed to said drum, as shown at 11 and its opposite end secured to a closure element 12 for the entrance

50 2. Moving the closure element away from the entrance will draw the polishing cloth exteriorly of the casing whereby said polishing cloth may be employed for rubbing or polishing shoes.

55 The closure element 12 has a chamber 13 to

removably receive a brush 14 which may be detached from the closure element when desiring to employ the brush upon shoes for the purpose of cleaning and polishing the latter. The head of the brush 14 is provided with a groove 15 aligning with keepers or notches 16 formed in the walls of the chamber 13 when the brush is placed therein. A bowed spring element 17 has its ends operating in the groove 15 and when flexed to lie parallel with the head of the brush the ends thereof enter the keepers or notches 16 to prevent accidental removal of the brush from the chamber. The head of the brush is provided with a bayonet slot 18 to receive the inner end of a button 19 slidably secured to the element 17 for retaining the latter in a flexed and parallel position to the brush head. By moving the button 19 out of the bayonet slot 18, the element 17 will assume a bowed position, as shown in dotted lines in Figure 2, moving the ends thereof out of the notches or keepers 16 freeing the brush for removal from the chamber 13.

5 A plate 20 is secured to the outer face of the closure element 12 and is cut out to permit the element 17 to extend therethrough when bowed and said plate when brought in engagement with the casing will provide thereto a side wall. Spring clips 21 are secured to the closure element and are adapted to snap into the notches 5 20 25 30 35 40 45 50 55 5 of Figure 1 to retain the closure element in a position for closing the entrance 2.

A guide plate 23 is mounted in the casing between the entrance 2 and the drum and has a slot 24 through which the polishing cloth extends. The guide 23 is supported by the plates 3 and the latter also support adjacent to the drum a tubular element 25, one end of which is exposed by an entrance 26 in one of the side walls of the casing.

The cylindrical element slidably supports a stick of shoe polishing substance 26, one end of which is engaged by a follower 27 slidably mounted in the tubular element 25 and has connected thereto a coil spring 28 which is in turn connected to one of the plates 3 and the end wall of the casing. The tubular element 25 by way of the entrance 26 receives a polish applying brush 29, the bristles of which engage with the polish 26'. The head of the brush 29 carries a stem 30 having angularly related faces and said stem extends through an opening in a closure cap 31 of the entrance 26. The outer end of the stem is equipped with a finger piece 32. The cap 31 is capable of sliding on the stem but is fixed

for nonrotation relative thereto and is provided with projections 33 adapted to be engaged with bayonet grooves 34 formed in the wall of the entrance 26 for removably securing the cap in entrance closing position. A coil spring 35 is mounted on the stem between the brush 29 and the cap. A turn of the finger piece 32 in one direction will disengage or free the cap and permit the removal thereof from the entrance along 10 with the brush 29 from the tubular element.

A fastener 36 is secured to the follower 27 and operates through slots 50 and 51 in the tubular element 25 and one of the side walls of the casing respectively and has secured thereto a finger 15 piece 38 whereby the follower may be manually slid to extend the polishing material 26' outwardly of the entrance 26, at the same time tensioning the spring 28 so that the latter will act to draw the follower inwardly of the tubular element when the finger piece 38 is released.

To permit positioning the finger piece 32 away from the cap 31 so that a firm hold may be obtained thereon, the stem 30 is slidable relative to the cap so that a person by sliding the finger 25 piece 38 in one direction will cause the follower through the stick of polishing material 26' to slide the brush 29 in the tubular element 28 and thus move the stem 30 through the cap 31 and bring about spacing of the finger piece 32 from 30 the cap 31. This gives indication to the operator that sufficient polish has been applied to the brush, and by turning the finger piece 32, the substantially rectangular shank 30 on said finger piece will cause the cap 31 to be turned to bring 35 its lugs or projections 33 out of the bayonet slots

34 so that the brush may be removed from the tube 25. The cap serves as a guard or protector for the hand of the operator when the polish from the brush is applied to a shoe and if desired may also serve as a hand grip for the brush. 5 It is to be understood that the brush 29 is employed for applying polish obtained from the stick 26' onto shoes while the brush 14 is employed for brushing the polish after its application to the shoes and to cause the applied polish 10 to shine the polishing cloth 10 is employed.

A device of the character described includes in a single kit all of the accessories necessary for cleaning and polishing shoes and when the accessories are assembled in the casing of the kit 15 they are prevented from contacting with other articles so that the device can be conveniently carried or stored in traveling bags, suitcases or the like.

Having described the invention, I claim:

In a device of the character described, and in combination, a container having an open end for a polish stick having means spring influenced in one direction in the container and movable by finger pressure in a second direction to move said polish stick, a cap closing the open end of the container and holding means operable by the turning of the cap for retaining the same on the container, a spring influenced, cross-sectionally square shank movable through a square opening in the cap, having a handle at its outer end and a brush carrying head on the shank, positioned for contact with the polish stick when arranged in the container.

JOHN G. HUMMEL. 35
